UNITED STATES PATENT OFFICE.

WILLIAM R. RUDOLPH, OF GLENBROOK, CONNECTICUT.

CHRISTMAS-TREE ORNAMENT AND METHOD OF MAKING SAME.

1,351,790.

Specification of Letters Patent.

Patented Sept. 7, 1920.

Application filed June 24, 1919. Serial No. 306,338.

To all whom it may concern:

Be it known that I, WILLIAM REYNOLD RUDOLPH, a citizen of the United States, residing at Glenbrook, in the county of Fair-
field, State of Connecticut, have invented certain new and useful Improvements in Christmas-Tree Ornaments and Methods of Making Same; and I do hereby declare the following to be a full, clear, and exact de-
scription of the invention, such as will enable others skilled in the art to which it ap-
perts to make and use the same.

This invention relates to new and useful improvements in ornaments and particu-
larly to Christmas tree ornaments.

One object of the present invention is to provide a novel and ornamental device which is adapted to be hung on a Christmas tree, and which is formed from a number 20 of narrow strips of paper folded in a peculi-
ar manner.

Another object is to provide a novel and improved device of this character which can be easily made by hand, and which is simple 25 and inexpensive in its construction, the device not requiring any paste or other adhesive to hold the parts together.

Other objects and advantages will be apparent from the following description when 30 taken in connection with the accompanying drawing.

In the drawing:

Figure 1 is a perspective view of the com-
pleted ornament.

Fig. 2 is a perspective view of the strips 35 of paper disposed in the position assumed in the first step in the folding of the orna-
ment.

Fig. 3 is a perspective view of the next 40 step in the folding of the ornament.

Fig. 4 is a perspective view of the device showing the next step in which the peripheral points are being formed.

Fig. 5 is a perspective view of the device 45 showing the next step in which the points on the side faces of the ornament are being formed.

Referring particularly to the accompany-
ing drawings there are shown four elongated 50 strips of paper folded or doubled and inter-
woven at 10, so as to produce the upper radi-
al ends 11, 12, 13, and 14, and the lower radi-
al ends 15, 16, 17, and 18. The end 13 is
then folded over alongside of the ends 11,
55 and 15 and parallel therewith, after which
the end 12 is folded parallel with 18, 11,

parallel with 17, and 14 parallel with 16. The end 14 is tucked under the end 13 ad-
jacent the last-named fold of the said end, and the strips drawn tightly together at the 60 center so as to provide a square composed of four smaller squares. The end 11 is now folded under on the oblique line 19 so that said end is parallel with the strip 18. The end 11 is then folded over on the oblique 65 line 20 so that it is parallel with the end 15 and above the ends 12 and 18, after which the strip is folded on the line 21 so that it lies longitudinally on the end 15. The end 11 is then slipped under the strip 14 adjacent 70 the first fold thereof and pulled through, forming the point 22. Each of the strips 12, 13, and 14 is folded and tucked in in the same manner with the result that there will be one point 22 on each of the four sides 75 of the large square, first-mentioned. Each of the ends 15, 16, 17, and 18 is then treated in the same manner as 11, 12, 13, and 14, to produce the remaining of the points 22. The ends 11, 12, 13, and 14 are then rolled 80 into the points 23, on one side face of the large square and then slipped under the nearest smaller square which stands at right angles to the one from which the end ex-
tends. The ends 15, 16, 17, and 18 are then 85 similarly manipulated on the other side face of the large square, to form the points 24. The ends 11, 12, 13, 14, 15, 16, 17, and 18 will then project from the first points 22, when such remaining end portions are cut 90 off even with the oblique edges of the points 22. The device will then appear as shown in Fig. 1.

By forming the device of differently col-
ored strips of paper a very pleasing effect 95 is obtained, and a beautiful ornament for hanging on the Christmas tree is produced.

What is claimed is:

1. An ornament comprising a flat body having a plurality of edge faces with pairs 100 of radiating points extending from said edge faces, and a plurality of conical points projecting from the opposite flat faces of the body.

2. An ornament comprising a flat body 105 of rectangular outline, a pair of points ex-
tending from each side edge of the body and in the plane of the body, and a plurality of conical members projecting from each of the flat faces of the body.

3. The method of forming a Christmas tree ornament consisting of interweaving a

plurality of doubled strips of paper, folding the strips on oblique lines adjacent the interweaving, tucking the ends through the interweaving, and folding the ends on both 5 sides of the interweaving into conical members and tucking the ends in the interweaving.

In testimony whereof, I affix my signature in the presence of two witnesses.

WILLIAM R. RUDOLPH.

Witnesses:

CHARLES R. PETTY,
FRED GREENWOOD.
